UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

METHOD OF MANUFACTURING TROLLEY-WIRE SUPPORTS.

Application filed August 30, 1923. Serial No. 660,221.

To all whom it may concern:

Be it known that I, SAMUEL S. MATTHES, a citizen of the United States of America, residing at Mansfield, in the county of 5 Richland and State of Ohio, have invented certain new and useful Improvements in Methods of Manufacturing Trolley-Wire Supports, of which the following is a specification.

10 My invention relates to the method of constructing conductor supports and has particular reference to that class of supports adapted to engage and secure the trolley wire to a hanger or other support.

15 The object of my invention is to produce a device of the class described which will be simple, strong, and economical as to cost of production.

20 My invention resides in the method of producing the device herein described, as set forth in the various steps.

In the drawing accompanying this specification:

25 Fig. 1 shows a side plan view of a device constructed as described.

Fig. 2 is an end view in elevation of Fig. 1.

Fig. 3 is a sectional view of Fig. 1 on the line 3—3.

30 Fig. 4 is a side plan view of the upper supporting element of Fig. 1.

In the preferred form of a device embodying my invention, I employ two members, namely: an upper supporting member 35 1 and a lower supporting member 2. I prefer to make the member 1 of malleable cast iron or of an iron forging in order to reduce the cost of material used in the member 1. The member 2 is invariably made 40 of copper or some copper base alloy, and for that reason, is the expensive element of the device.

The upper supporting member 1 is divided 45 with a boss member 3, which is recessed and internally threaded as indicated at 4, in order to provide means for securing the device to an overhead hanger. The member 1 is also provided with diametrically opposite projecting arms 5—5 and each arm is provided at its end with an aperture 6.

50 The lower supporting member 2 is divided with a longitudinally extending channel or groove 7 formed by the depending lips 8—8 and which are cast open as indicated by

the dotted lines 8' in Fig. 3 and adapted to be formed above the conductor 9 after the same has been positioned within the groove 7 as shown in Fig. 3. The member 1 is also provided with upstanding securing members 10—10 which co-operate with the extreme ends of the members 5 on the member 1 to unite the members 1 and 2 into a unitary device.

55 In the method of constructing my invention, I first produce the member 1 by any of the well known methods for such operations, as by casting of malleable cast iron or drop forging from iron or steel. The member 1 is then placed in a mold having 60 a recess therein which conforms to the complete device, the member 1 being placed in that portion of the recess which conforms to its shape. The balance of the recess is then filled with molten copper or copper 65 base metal, preferably at a high temperature, and this forms the lower supporting member 2 and simultaneously unites it to the upper supporting member 1. I find 70 that it is advisable under some conditions to have the member 1 heated at the time the member 2 is formed from the molten metal and I have also found that under some 75 conditions, there is an advantage in having the exposed faces of the member 1 which 80 are engaged by the molten copper or bronze covered with a metal of lower melting point than that of member 1 and such covering metal may be a low melting spelter or 85 brazing metal such as a mixture of copper 90 and zinc and well known in the arts, or the coating metal may be of tin which has been thoroughly applied to the exposed engaging surfaces of the member 1. The 95 coating metal may be applied in various ways, as by the oxy-acetylene process, electric arc process or by dipping in the molten coating metal. The aperture 6 permits the 100 molten copper or bronze to form a positive lock with the member 1. The parts after being removed from the mold will have the members 10—10 "dropped" to cause them under some conditions to make better and 105 more secure engagement with the arms 5—5 and this is advisable where the ends of the arms 5—5 have not been coated as previously described.

110 There are, of course, variations which may be made in my method of construction which will suggest themselves to those

skilled in the art, especially variations as to the method of uniting the parts together, but such variations may fall within the scope of my invention.

5 The member 3 may be recessed and threaded prior to or after the members 1 and 2 have been secured together.

I find that the method of constructing an ear as above described produces a device 10 which is very strong and economical and reliable in service.

I claim:

1. A trolley wire supporting device comprising two supporting members, one to engage and support a trolley wire and the other to engage and support the first member, the members being cast together. 15

2. A trolley wire supporting device comprising a member of malleable iron to se-

cure the device to a support and a bronze 20 member interlocked and cast therewith to engage and support the trolley wire.

3. A trolley wire supporting device comprising a member of malleable iron to secure the device to a support, recesses formed 25 therein, and a bronze member to support a conductor interlocked with the recesses of the first member by being cast therewith.

4. A trolley wire supporting device comprising a malleable iron member to secure 30 the device to a support, recesses formed therein, and a bronze member to engage and support a conductor interlocked therewith and the metal of the bronze member continuous through the recesses. 35

In testimony whereof I affix my signature.

SAMUEL S. MATTHES.
